COIN RECEPTACLE AND UNLOCKING DEVICE THEREFOR

Filed July 15, 1922.

Patented Feb. 10, 1925.

1,525,947

UNITED STATES PATENT OFFICE.

JOHN EDWARD MITCHELL, OF LAKEWOOD, OHIO, ASSIGNOR, BY MESNE ASSIGNMENTS,
TO ALVIN R. MARTINE, OF CLEVELAND, OHIO.

COIN RECEPTEACLE AND UNLOCKING DEVICE THEREFOR.

Application filed July 15, 1922. Serial No. 575,285.

To all whom it may concern:

Be it known that I, JOHN EDWARD MITCHELL, a citizen of the United States, residing at Lakewood, in the county of Cuyahoga and State of Ohio, have invented a certain new and useful Improvement in Coin Receptacles and Unlocking Devices Therefor, of which the following is a full, clear, and exact description, reference being had to the accompanying drawings.

This invention relates generally to that class of receptacles commonly referred to as home savings banks or pocket coin receptacles and it has to do more particularly with a locking closure therefor and with an unlocking device for the closure.

In receptacles of the foregoing class which are used by depositors of banking institutions for accumulating small change therein, to be deposited in the bank from time to time and which upon being presented to the teller of the bank have to be opened and closed with considerable dispatch, the facility and speed with which the closure may be removed and replaced is of great importance. It is to this variety of receptacles that my invention particularly relates, and to the attainment of the foregoing ends that it was conceived.

My aims are to provide a closure that may be very readily applied to a receptacle wherewith it is designed for use and which incorporates simple yet highly efficient locking means for securing the closure to the receptacle; and to provide an inexpensive and simply constructed unlocking device that is particularly convenient of manipulation that may be used for removing the closure from the receptacle.

Other and more specific objects will become apparent as I proceed to describe the present preferred embodiment of the invention, reference being had to the accompanying drawing in which similar reference characters designate corresponding parts throughout the several views and wherein Fig. 1 is a perspective view of a coin bank or receptacle having the cover applied thereto; Fig. 2 is a similar view of the unlocking device; Fig. 3 is a fragmentary side elevation of the receptacle with the unlocking device applied to the cover thereof; Fig. 4 is a sectional edge elevation of what is shown in Fig. 3, the plane of section through the

unlocking device being designated by the line 4-4 of Fig. 3, while the receptacle and its closure are shown in elevation; Fig. 5 is a fragmentary side elevation of the receptacle with the closure removed; Fig. 6 is a view of the unlocking device as though looking into the jaws thereof; Fig. 7 is an enlarged sectional detail through the receptacle, its closure, and the adjacent parts of the unlocking device, this section also being on the line 4-4 of Fig. 3; and Fig. 8 is a perspective view of the closure with a part broken away to more clearly reveal the locking element.

The receptacle wherewith I have shown my improvements associated is practically identical with that disclosed in Jacobsen Patent No. 1,412,526, issued April 11, 1922, except for the locking means incorporated in the closure. Inasmuch as the receptacle, generally, constitutes no part of my present invention, it will suffice to briefly describe it as comprising a central partition 1 and side walls 2 which are spaced from the opposite sides of the partition to provide coin receiving spaces between the walls and partition. According to the present design, these spaces are divided into magazines having a width slightly greater than the diameter of the coin, and the walls and partition are provided with slots that are less in width than the magazines so that the coins in the receptacle may be readily seen. The magazines are open at both ends, and at the receiving end are provided with retaining means (not shown) which will admit of the insertion of coins but prevent their withdrawal. Designed to fit over the discharge end of the receptacle is a closure 5 (shown in perspective in Fig. 8) which comprises side walls 6, a bottom wall 7, and end walls 8. A locking element 10 occupies the closure and the same is of resilient metal and in the form of a channel, the web 11 whereof is secured, as by rivets 12, to the bottom wall 7 of the closure. The side flanges 13 of the locking element are comparatively shallow, but extending therefrom to within a short distance of the plane of the open side of the closure are a plurality of locking fingers 14 which have lips 15 turned outwardly from their upper end, the fingers along one side of the locking element being directly opposed to those on the

other side. In transverse alignment with the fingers 14, are apertures 16 in the side walls 6.

Spaced upwardly from the lower edges of the side walls 2 of the receptacle a distance substantially equal to that between the lips 15 and the bottom wall 7 of the closure are a plurality of slots 20 for the reception of the lips 15 of the locking device when the closure is applied to the receptacle. The aforesaid edges of the side walls 2 are provided with notches 21 which lead into the slots 20; and the central partition 1 is shown as having notches 22 in transverse alignment with the notches 21 of the opposed side walls.

It will be understood from the foregoing that when the closure 5 is applied to the receptacle the lips 15 of the fingers 14 will enter the slots 20 of the side walls 2 and bear against the inner surfaces of the walls 6 of the closure thereby to securely lock the closure to the receptacle, it being explained that the lips 15 are of a length substantially equal to that of the slots 20.

According to the present preferred embodiment of my invention as it pertains to the unlocking device, I employ as the major part of that device a standard type of paper clamp which comprises opposed plates 25 that terminate in handles 26 engaged through slots 27 in a substantially cylindrical spring 29 that is split along one side and has its edge portions 30 bearing upon the plates 25 adjacent their free edges. The spring 29, therefore, tends to force the free edges of the plates toward each other, and a reverse action may be accomplished by forcing the handles 26 toward each other in opposition to the spring 29 all of which will be readily understood because of the general familiarity with clamps of this character.

Secured, as by rivets 35, to the free edges of the plates 25, are jaws which have end flanges 37, teeth 38 disposed along their front edges, and interengaging stops 39 suitably arranged along their rear edges. The spacing of the teeth 38 is identical with the spacing of the aperture 16 of the closure 5.

When it is desired to remove the closure, the jaws of the clamp are opened by pressing the handles 26 toward each other and the jaws are presented on opposite sides of the closure with their teeth 38 in register with the apertures 16, a condition which is readily brought about by the fact that the jaws are accurately positioned with respect to the closure by their end flanges 37 engaging the ends of the closure and the stops 39 contacting with the bottom wall of the closure. Now, upon releasing the handles 26, the spring 29 forces the jaws 36 together so that the teeth 38 are projected through the

apertures 16 and into engagement with the fingers 14, as clearly illustrated in Fig. 7; and the superior tension of the spring 29 overcomes that of the fingers 14 causing the fingers to yield and retract their lips 15 from the slots 20. With the parts in this condition, the closure may be readily withdrawn from the receptacle, the notches 21 in the side walls 2 accommodating the teeth 38 during such withdrawal. The central partition 1 is notched at 22, as previously explained, so as to avoid any possible interference of said partition with the complete retraction of the fingers 14.

The cover, with the unlocking device applied thereto, may be laid aside until the receptacle has been emptied of its contents, after which the closure may be replaced conveniently by means of the unlocking device, which serves to hold the fingers 14 inward while the cover is being applied. Upon the removal of the unlocking device, the fingers will spring back to normal position with their lips in the slots 20.

While I have described the present embodiment of my invention in detail, it will be understood that I do not limit myself to the structural features thereof further than is required by the terms of the appended claims.

Having thus described my invention, what I claim is:

1. In combination with a receptacle having the edge of one of its walls provided with a notch and holding means inwardly of said notch, a cover for the receptacle having a part overlying the outer side of said wall, said part having an aperture registering with the notch, a locking element carried by the cover and disposed, when the cover is in place, on the inner side of said wall, said element having a part interlocking with the holding means of the wall, and means adapted to be projected through the aforesaid aperture and through the notch for disengaging the locking element from the holding means, to the notch accommodating said means during the withdrawal of the cover from the device.

2. In combination with a receptacle having the edge of one of its walls provided with a notch which is enlarged at its inner end, a cover for the receptacle having a part overlying the outer side of said wall, said part having an aperture registering with the notch, a locking element carried by the cover and disposed, when the cover is in place, on the inner side of said wall, said element having a part that enters the enlarged inner end of the notch, and means adapted to be projected through the aforesaid aperture and through the notch for disengaging the locking element from the notch, the notch accommodating said means during the withdrawal of the cover from the receptacle.

3. In combination with a receptacle having an open end, a closure arranged to telescope over said open end, the edge portions of the opposed walls of the receptacle being provided with holding means, locking elements carried by the closure, said locking elements being disposed on the inner sides of said walls when the closure is applied to the receptacle and having parts that interlock with the holding means of the opposed walls, thereby to lock the closure to the receptacle, the closure having apertures in substantially transverse alignment with the locking elements, and a device designed to embrace the closure and having parts arranged to enter the apertures of the closure and engage the locking elements thereby to release them from the aforesaid holding means.
- 20 4. In combination with a receptacle having an open end, a closure arranged to telescope over said open end, the edge portions of the opposed walls of the receptacle being provided with notches that are enlarged at their inner ends, locking elements carried by the closure, said locking elements being disposed on the inner sides of said walls when the closure is applied to the receptacle and having parts that enter the enlarged inner ends of the notches thereby to lock the closure to the receptacle, the closure having apertures registering with the aforesaid notches, and a device designed to embrace the closure and having parts arranged to enter the apertures of the closure and engage the locking elements thereby to retract them from the notches.
5. In combination with an open-ended receptacle having notches in the edges of its opposed walls and slots adjacent the inner ends of the notches, a closure designed to telescope over the open end of the receptacle and having apertures in register with the notches, resilient locking elements carried by the closure and having parts which engage within the slots, and an unlocking device arranged to embrace the closure and having parts which are projected through the apertures of the closure into contact with the opposed resilient locking elements thereby to retract them from the slots.
6. In combination with an open-ended receptacle having notches in the edges of its opposed walls, the notches of the opposed walls being substantially in transverse alignment and enlarged at their inner ends, a closure designed to telescope over the open end of the receptacle and having apertures in register with the notches, a resilient locking element carried by the closure and having opposed parts which engage within the enlarged inner ends of the notches, and an unlocking device arranged to embrace the closure and having parts which are projected through the apertures of the closure
- 10 into contact with the opposed parts of the resilient locking element thereby to retract said parts from the notches.
7. In combination with an open-ended receptacle having notches in the edges of its opposed walls, said notches being enlarged at their inner ends, a closure designed to telescope over the open end of the receptacle and having apertures registering with the notches, a resilient locking element that is substantially U-shaped in cross section and having its central portion secured to the closure while its opposed branches repose upon the inner sides of the receptacle walls when the closure is applied to the receptacle, the free ends of said opposed parts being provided with outwardly extended lips which enter the enlarged inner ends of the notches, and an unlocking device designed to embrace the closure and having parts which enter the apertures of the closure and engage the opposed parts of the locking element thereby to retract their lips from the enlarged inner ends of the notches.
8. In combination with an open-ended receptacle having a plurality of notches in the edges of its opposed walls, the notches of one wall being in substantially transverse alignment with those of the other, the notches being enlarged at their inner ends, a closure for application to the open end of the receptacle and comprising a bottom wall, side walls and end walls, the side walls having apertures which register with the aforesaid notches, a locking element consisting of a substantially channel shaped spring disposed within the closure and having its web secured to the bottom wall thereof, opposed tongues extending from the side flanges of the locking element in transverse alignment with the aforesaid notches, said tongues terminating at their free ends in outwardly extended lips which engage within the enlarged inner ends of the notches, and an unlocking device having opposed jaws provided with teeth, the device being designed to cooperate with the closure in such manner as to cause said teeth to register with and enter the apertures in the opposed side walls of the closure and engage the opposed tongues of the locking element thereby to retract their lips from the enlarged inner ends of the notches.
9. In combination, a receptacle, a closure therefor, locking means for securing the closure to the receptacle, and a clamping device for application to the closure, said device, when applied to the closure, cooperating with the locking means to release it thereby to permit the withdrawal of the closure.
10. In combination with a receptacle equipped with a closure and provided on its interior with locking means for securing the

- closure to the receptacle, the closure having on its opposite sides apertures through which the locking means may be manipulated for releasing the closure, and an unlocking device having opposed parts which are adapted to be projected through the apertures of the closure for manipulating the unlocking means and releasing the closure from the receptacle.
- 10 11. In combination with a receptacle equipped with a closure and provided on its interior with locking means for securing the closure to the receptacle, the closure having on its opposite sides apertures through 15 which the locking means may be manipulated for releasing the closure, and an unlocking device having opposed jaws provided with teeth arranged to enter the apertures of the closure and manipulate the locking means thereby to release the closure from the receptacle, the unlocking device co-operating with the closure in such manner as to properly position its teeth with respect to the apertures of the closure.
- 20 12. In combination with a receptacle equipped with a closure and provided on its interior with locking means for securing the closure to the receptacle, the closure having on its opposite sides apertures through 25 which the locking means may be manipulated for releasing the closure, and an unlocking device in the nature of a spring clamp having opposed jaws that are provided with

teeth arranged to enter the apertures of the closure and manipulate the unlocking means 35 thereby to release the closure from the receptacle when the unlocking device is clamped to the closure.

13. In combination with a receptacle equipped with a closure and provided on its 40 interior with locking means for securing the closure to the receptacle, the closure having on its opposite sides apertures through which the locking means may be manipulated for releasing the closure, an 45 unlocking device in the nature of a spring clamp incorporating opposed clamping plates and a substantially cylindrical spring embracing said plates and maintaining them in operative relation and tending to force 50 their free edges toward each other, and jaws applied to the opposed free edges of the clamping plates, the opposed jaws having teeth that are adapted to be projected by the action of the spring clamp through 55 the apertures in the closure and manipulate the locking means thereby to release the closure from the receptacle, the jaws being designed to cooperate with the closure in such manner as to properly position the 60 teeth with respect to the apertures of the closure.

In testimony whereof, I hereunto affix my signature.

J. EDWARD MITCHELL.
